F. H. Moore

UNITED STATES PATENT OFFICE.

F. H. MOORE, OF BOSTON, MASSACHUSETTS.

STAIR-SWEEPER.

Specification of Letters Patent No. 22,301, dated December 14, 1858.

To all whom it may concern:

Be it known that I, F. H. MOORE, of Boston, in the county of Suffolk and State of Massachusetts, have invented a new and Improved Stair-Sweeper, of which the following is a full, clear, and exact description, reference being had to the accompanying drawings, making part of this specification, in which—

10 Figure 1 is a longitudinal vertical section. Fig. 2 is a transverse vertical section on the line z , z , of Fig. 1.

In using the ordinary hand dust pan, the dust is liable to be swept over the person and 15 dress of the operator, and also to rise in the room and settle upon the furniture.

To obviate these objections is the object of 20 my present invention, which consists in operating the brush within a box or cover which prevents the escape of the dust, as will be more fully set forth hereafter.

That others skilled in the art may understand my invention I will proceed to describe the manner in which I have carried the same 25 into effect.

In the said drawing A represents a tread of a step, B is a box of tin or other suitable material the bottom being open for a considerable portion of its length or from a , to 30 b , the remainder of the length is occupied by a pan C, the back c , of which forms one end of the box and has attached to it a handle D. The sides d , of the pan fit within the sides of the box B, and have secured to them 35 small tubes e , e^2 . A rod f , is attached at one end at 5, to each of the sides of the box, so that when the pan is inserted into the end of the box, in the position shown in the drawings, the rod f , enters the upper tube e . 40 This and a turnbuckle g , on the back c , of the pan secures it in place. The front edges 6, of the sides of the pan are curved out to fit the front of the step A. When however the pan is to be used on a level surface in- 45 stead of on the stairway, the pan C, is inserted into the end of the box higher up, so that the bottom of the pan shall be at a level with the lower edges of the box B, when the rods f , will enter the lower tubes e^2 .

50 In the top of the box B, is formed a longitudinal slot h , which extends nearly the whole length of the top of the box or from a^2 , to b^2 , and is of sufficient width to allow

free play to the handle k of the brush E, which is inserted from the lower side of the 55 box. To prevent the dust from rising through this slot, it is covered by a curtain F, which is hung loosely on rods l , by rings i ; these rods are placed one on each side of the slot, and are secured to the ends of the 60 box B. The handle k , of the brush is passed through a hole m , in the middle of the curtain. The curtain is made so long that the brush may be moved freely along in the slot h , without uncovering the slot. 65

Operation: If the stairs are to be swept, the pan C is placed in the position shown in the drawings. The operator holding the pan with one hand by the handle D, with the other hand moves the brush E, back and forth in the box as in the ordinary method of sweeping, the handle k , sliding back and forth in the slot h ; the length or fullness of the curtain F allows of this motion without uncovering the slot h . When a level surface 70 as a portion of the floor of a room is to be swept, the pan C, is moved up to its other position or with the rods f , in the tubes e^2 , and the brush is operated in a similar manner. When the sweeping is completed the 75 pan C, may be removed from the box, by turning the buckle g and drawing out the pan.

Instead of having the slot h , in the top of the box it may be placed in the side, and a 80 brush may be used which has its bristles set at right angles to the axis of the handle. 85

The pan C, may be adjusted by means of slots and pins so that it may be varied in position and accommodate itself to the width 90 of step.

What I claim as my invention and desire to secure by Letters Patent is—

1. The combination of the box B, and brush E, with the dust pan C, arranged and operating in the manner substantially as described whereby the dust is prevented from escaping as set forth. 95

2. And in combination with the above I claim the curtain F operating substantially 100 in the manner specified.

F. H. MOORE.
